P. MILLER

EXPANDING REAMER

Filed Nov. 23, 1922

INVENTOR.
Paul Miller
BY Verona E. Miller
his ATTORNEY

UNITED STATES PATENT OFFICE.

PAUL MILLER, OF PHILADELPHIA, PENNSYLVANIA.

EXPANDING REAMER.

Application filed November 23, 1922. Serial No. 602,917.

To all whom it may concern:

Be it known that I, PAUL MILLER, a citizen of the United States, residing at Philadelphia, in the county of Philadelphia and State of Pennsylvania, have invented certain new and useful Improvements in Expanding Reamers, of which the following is a specification.

My invention relates to expanding 10 reamers.

The object is to provide a tool of the character described capable of being made in different sizes, and including comparatively few parts, it being easy to construct, accurate and effective in operation, and durable and perfectly rigid when the parts comprising it are assembled and locked together.

In the accompanying drawings:—

Fig. 1 is a view in side elevation, partly 20 in section;

Fig. 2 is a transverse section on the line 2—2 of Fig. 1;

Fig. 3 is a view of the body in longitudinal section;

Fig. 4 is a view of the lock nut;

Fig. 5 is a view of the round steel plate for supporting the outer end of the centering rod;

Fig. 6 is a view of the round nut;

Fig. 7 is a view of the cones;

Fig. 8 is a view of one of the blades;

Fig. 9 is a view of the hand-operated arbor.

A, represents the body of the tool. This 35 is preferably made of steel with a taper 1 at one end, and 2, at the other, and having two cylindrical portions 3 and 4 of different diameters, and between them the shoulder 5, all constituting the bore of the tool through 40 its longitudinal or axial center.

B, represents a center guiding rod having threads 6 and 7 at its opposite ends, and the cylindrical portion 8 adjacent to the threads 7, and of a size to fit snugly the cylindrical bore portion 3 of the body A of the tool, as 45 shown in Fig. 1. One side of this collar 8 is grooved or flattened as at 9 to receive the screw 10 which turns in the threads 11 in the side of the tool, and extends to the flat or 50 the bottom of the groove 9 to hold the rod B rigidly in place in the actual center of the bore of the body of the tool. One or more tapering cones C' and C² (two being 55 shown) are bored to fit the center guiding-bar B to adjust the blades D from the center.

It is obvious that any number of blades might be employed. Radial grooves 12 are provided for them, (which grooves the blades accurately fit), their inner edges 13 sloping diagonally to correspond to the 60 tapering surfaces of the cones. Against these inner edges 13 the cones bear, so that as the cones are moved inwardly along the center guiding-rod B, the blades are forced outwardly simultaneously, with precision, 65 all of them the same distance, and uniformly from end to end.

The construction of these tapering cones and the other parts of the tool are such that it is possible to expand the blades D to any 70 required size, for example, from one inch and more, to two and one-half inches, to an adjustment of one-thousandth part of an inch.

The cones C' and C² are moved inwardly 75 on the center guiding-rod by a round nut 14 having a threaded hole 15 at the center, and two holes 16 at the sides to receive a tool for turning the same.

The extreme outer end 17 of the center 80 guiding rod is supported in the center hole 18 of the round steel plate 19. The periphery of this plate is screw-threaded as at 20, and it is secured in place by inserting the point of a wrench in the hole 21. This 85 round plate not only holds and supports the outer end of the center guiding rod, but is also employed to tighten the blades D from inside the body A.

In addition to the round plate 19, the 90 outer threads of which screw into the threads 23 of the body, there are two round nuts 24 and 25, which turn on threads 26 and 27 on the body portion respectively at the opposite ends of the steel blades, their 95 function being to tighten and hold the blades in the grooves from their opposite ends after they shall have been equally expanded and adjusted outwardly.

E, is a shank for the steel body A, it preferably having the two tapering ends 28 and 29 with the threaded socket 30 in the taper 28. The taper 28 fits the taper 2 of the body, and the threads 30 screw on the threaded end 7 of the center guiding rod B, 105 and the radial slots 31 and 32 receive a key for locking the shank and body axially together, while the set-screws 33 in the body hold the shank rigidly in place.

The shank F is of similar construction to 110

the shank E, except that the latter is adapted for the Morse or other taper for machine reaming, and shank F has a square end 34 for hand reaming.

5 It is understood that these reamers may be made in various sizes, and a set of five or six marked from one to five or six on the bodies will do the work that heretofore it required sixty times the number of tools 10 to do, my present reamer being made to ream any required size hole from one and one-half to eight and one-half inches in diameter with an adjustment of from one-thousandth of an inch upward.

15 I claim:

1. An expanding reamer including a body having a bore formed throughout its center, a portion of which is cylindrical, a center guiding rod having a cylindrical portion 20 which fits and is held in the cylindrical portion of the bore, and provided with screw-threads at each end, radially adjustable blades, cones slidably mounted on the rod for engaging the inner edges of the 25 blades, and simultaneously adjusting them uniformly throughout their length, a nut screwed on the threads of the rod for adjusting the cones, and a shank having a portion which fits one end of the bore of the 30 body portion and provided with a screw-threaded socket which receives one of the threaded ends of the center guiding rod.

2. An expanding reamer, including a counter-bored body, a portion of which is 35 radially slotted, a portion of the bore cylindrical and a part tapered, a center guiding rod fitted to the cylindrical portion of the bore, means for centering and supporting the outer end of the rod with respect to the 40 body portion, and a shank having a tapered end adapted to fit the tapered portion of the bore of the body portion and means for securing the adjacent ends of the center guiding rod and the shank together.

45 3. An expanding reamer including a counter-bored radially slotted body portion, a shank having a portion which extends into the bore of the body portion, a rod located at the axial center of the bore and secured 50 to the shank, blades fitted to and adjustable in the slots and having tapering inner edges, graduated cones slidably mounted on the rod and engaging the tapering inner edges of the blades, the rod having a screw-threaded outer end, a nut screwed on the 55 threads for moving the cones in a direction

toward the shank to simultaneously adjust the blades.

4. An expanding reamer including a counterbored radially slotted body portion, 60 one end of the bore tapered, a shank having a tapering end fitted to the tapered bore, a center guiding rod coinciding with the axial center of the body portion and having one end secured to the contiguous end of the shank, said rod having a threaded outer end, blades fitted to and slidably mounted in the radial slots, means slidably mounted on the center guiding rod for simultaneously adjusting the blades, and a nut 70 screwed on the threads at the outer end of the rod for forcing said slidable means endwise thereon.

5. An expanding reamer including a counterbored radially slotted body portion, 75 a shank having a portion which extends into one end of the bore of the body portion, a center guiding rod lying coincident with the axial center of the body portion and secured to the shank, blades fitted to and slid- 80 able in the slots and having tapering inner edges, slidably mounted means on the rod and engaging the inner edges of the blades, and means for adjusting the slidably mounted means on the rod for simultaneously adjusting the blades.

6. An expanding reamer including a counter-bored radially slotted body portion, an intermediate portion of the bore being cylindrical and one end of the bore gradually tapering from the cylindrical portion to the end, a center guiding rod insertable in the bore by way of said tapering portion of the bore, the guiding rod threaded at each end and having a cylindrical portion adjacent to the inner threaded end adapted to fit the cylindrical portion of the bore of the body and be secured therein, a nut screwed on the threads, blades fitted to and adjustable in the slots, elements slidably mounted on the rod engaging the inner edges of the blades and adjustable on the rod by the turning of the nut, and means for centering and supporting the outer end of the rod in the outer end of the body, a shank having a tapering end adapted to enter and fit the tapering portion of the bore of the body and having a threaded socket which receives and is screwed to the threaded end of the rod adjacent to the cylindrical part thereof.

In testimony whereof I affix my signature.
PAUL MILLER.
